ROLAND V. HUTCHINSON, OF LANSING, MICHIGAN, ASSIGNOR TO GENERAL MOTORS RESEARCH CORPORATION, OF DETROIT, MICHIGAN, A CORPORATION OF DELAWARE

SUPERCHARGER

Application filed August 6, 1927. Serial No. 211,150.

This invention relates to superchargers used on internal combustion engines as applied to automotive vehicles and particularly to a system of heating the supercharged mixture 5 prior to its reaching the intake manifold.

In the conventional internal combustion engine it is customary to apply heat from the exhaust gases to the incoming fuel mixture, but as far as I am aware this system has not 10 been adopted in connection with engines on which superchargers are used. It is accordingly one of the principal objects of the invention to construct a system which will be adapted to a supercharged engine and will 15 heat the fuel after it has been supercharged and prior to its entry into the intake manifold.

In carrying out the invention use is made 20 to carburetted fuel by the provision of a valve in the exhaust pipe which is controlled by a bellows operated by the pressure in the intake manifold. When the pressure in the intake manifold is high it will expand the bellows and by means of a suitable system 25 of linkage will swing the valve so that less hot exhaust gas is applied to the incoming mixture. When the pressure in the intake manifold is low, the bellows will collapse 30 and cause the valve to close and thereby shunt the greater portion of the hot gases so that the heat may be applied to the incoming fuel mixture.

In order to heat the carburetted gas, I 35 make use of a jacketed hot spot installed at the discharge opening of the supercharger. The exhaust gas is conducted to the hot spot by a pipe which is tapped into the exhaust manifold and returned from the hot spot to 40 the exhaust tube by means of a second pipe.

The control valve previously referred to is positioned in the exhaust tube between the entrance pipe from the manifold and the exit pipe to the exhaust tube.

The hot spot is square in cross section and 45 has a spring operated valve arranged therein, the function of which is to deflect such fuel as may lodge on the valve to the hot spot wall, strike it at high velocity and become further mechanically and thermally

pulverized after passing through the supercharger.

The invention is disclosed in the accompanying drawings in which:

Fig. 1 is a side view of the front portion 55 of an internal combustion engine showing the invention applied thereto.

Fig. 2 is a view of the structure of Fig. 1 looking from the left.

Fig. 3 is a sectional view through the hot 60 spot at the supercharger discharge substantially on the line 3—3 of Fig. 2 except that a portion of the left hand side of the figure is taken through the axis of the valve for purposes of clearer illustration.

Referring to the numbered parts on the drawings, 10 denotes an internal combustion engine such as used on a Buick automobile, 12 is the exhaust manifold, 14 the intake manifold and 16 the exhaust tube.

The supercharger of the present invention is shown as a whole at 18 and is positioned 70 at the front of the engine and driven from the usual crankshaft. The supercharger has the customary inlet 20 from the carburetor and the outlet 22 leading to the engine. At the outlet 22 there is provided a jacketed hot 75 spot 24, the inner portion 26 of which is square in cross section and has a valve 28 fixed to a stem 30 to the exposed end of which there is applied a spring 31 which will normally hold the valve in the position shown in Fig.

2. As the carburetted air is drawn through the supercharger it may carry along therewith some entrained fuel and the function 85 of the valve is to deflect such fuel to the hot spot wall at a high velocity in order that it may become mechanically pulverized before reaching the firing chambers.

The jacket of the hot spot is shown at 32 90 and has an entrance 34 and an exit 36. Exhaust gases are led to the entrance 34 by means of the pipe 38 which communicates as at 40 with the exhaust manifold. From the outlet opening 36 the exhaust gases are led 95 back to the exhaust tube 16 through the pipe 40. As will be seen from Figs. 2 and 3 the jacket 32 and inner portion 26 are spaced to provide for the channel 42 through which the hot exhaust gases may circulate.

In order that the hot exhaust gas applied to the hot spot may be regulated, the following mechanism is provided. Mounted by means of a saddle 46 on a pipe 44 forming a part of the intake 14 is a bellows 48 which communicates with the interior of the pipe 44 by means of the opening 50. Inasmuch as the pipe 44 is the direct connection between the intake manifold 14 and the supercharger 10 the pressure in both pipe 44 and the manifold will be substantially the same. The interior of the bellows 48 is therefore subject to intake manifold pressure.

The saddle 46 is provided with an upstanding arm 52 to the upper end of which there is pivoted a short link 54 which in turn is pivoted to a link 56 extending across the upper portion of the bellows and having attached at its central portion a short link 58 pivoted to an ear 60 secured on the upper portion of the bellows. The opposite end of the link 56 has pivoted thereto as at 62, a suitably shaped link 64, the lower portion of which is pivotally attached as at 66 to a lever 25 68 secured to a shaft 70, extending through the exhaust tube 16 and to which there is secured a valve 72. From the structure just described it will be apparent that when the pressure in the pipe 44 increases it will cause 30 the bellows 48 to expand and thereby cause the valve 72 to more and more assume the dotted line position shown in Fig. 1. On the other hand the contraction of the bellows 48 will cause the valve to swing in the opposite direction until it assumes its maximum closed position as shown in Fig. 1. The position of the valve 72 will determine the proportion of exhaust gas which passes through the pipes 38 and 40 and circulates around the 40 hot spot, and the proportion of hot gas so circulating will depend entirely upon the intake manifold pressure. While the pressure is very low all the hot gas will be forced through the hot spot but when it is high very 45 little exhaust gas will be caused to circulate through the hot spot jacket.

It will be seen from the above description that a means has been provided for automatically regulating and governing the 50 amount of hot exhaust gas which will circulate through the hot spot jacket. This feature is important for when the pressure in the intake manifold is high it is desirable that less heat be applied to the incoming carbureted mixture, while when the pressure is 55 low it is preferable to have a considerable portion of heat applied to the fuel mixture. As far as I am aware no previous construction has incorporated heat control in connection with a supercharged engine.

I claim:

1. In combination with an internal combustion engine having a carburetor, a supercharger positioned between the carburetor and engine, a heater for the carburetted

fuel independent of the supercharger and positioned at the supercharger outlet, means for conducting the fuel to the engine, and means in the heater for pulverizing the unvolatilized fuel.

2. In combination with an internal combustion engine having a carburetor, a supercharger positioned between the carburetor and engine, a heater for the carburetted fuel independent of the supercharger and positioned at the supercharger outlet, means for conducting the carburetted fuel to the engine, and a valve in the heater for pulverizing the unvolatilized fuel.

3. In combination with an internal combustion engine having a carburetor, a supercharger positioned between the carburetor and engine, a heater for the carburetted fuel independent of the supercharger and positioned at the supercharger outlet, means for conducting the fuel to the engine, and a resiliently held valve in the heater for pulverizing the unvolatilized fuel.

4. In combination with an internal combustion engine having a carburetor, a supercharger positioned between the carburetor and engine, a heater for the carburetted fuel independent of the supercharger and positioned at the supercharger outlet, means for conducting the fuel to the engine, and a resiliently held flat valve extending entirely across the fuel passage in the heater for pulverizing the unvolatilized fuel.

5. In combination with an internal combustion engine having a carburetor, a supercharger positioned between the carburetor and engine, a heater for the carburetted fuel independent of the supercharger and positioned at the supercharger outlet, means for conducting the fuel to the engine, means in the heater for pulverizing the unvolatilized fuel, means for conducting exhaust gas to and from the heater, and means for automatically controlling the flow of exhaust gas from the pressure in the intake manifold.

In testimony whereof I affix my signature,
ROLAND V. HUTCHINSON.
